UNITED STATES PATENT OFFICE.

MARIUS C. A. LATOUR, OF PARIS, FRANCE.

AMPLIFYING APPARATUS.

1,382,738.

Specification of Letters Patent. Patented June 28, 1921.

Application filed June 8, 1918. Serial No. 239,019.

To all whom it may concern:

Be it known that I, MARIUS C. A. LATOUR, a citizen of the Republic of France, residing at Paris, France, 10 Rue Auber, have invented certain new and useful Improvements in Amplifying Apparatus, for which I have filed applications in England September 12, 1917, Patent No. 129,659, and in France September 12, 1916, of which the following 10 is a specification.

This invention relates to an improvement in or modification of the amplifying devices described in the specification of my prior patent application No. 209,269 filed December 28, 1917.

It is well known that the use of thermionic amplifiers is impeded by sounds of whistling, grating, etc., which are sometimes heard and which are very prejudicial to the 20 normal working of the apparatus; these abnormal phenomena have been attributed to the setting up of oscillations in the thermionic lamp facilitating the production of vibration or auto-excitation, but their source 25 is obscure and not entirely understood.

In the said prior specification a means of obviating these undesirable noises in the amplifiers has been indicated consisting in defining the potential of the casings, frames 30 or cores of the transformers and of the primary of the first transformer which supplies the current that is to be amplified.

According to the present invention an improved elimination of these objectionable 35 noises is obtained by defining also the potential of the frame or casing of the telephone headpiece and in some cases also the potential of the operator. A still further improvement is sometimes obtained by defining 40 also the potential of the earth with respect to the system. This is attained by connecting one pole of the main battery to the earth.

The present invention is illustrated in the accompanying drawing by way of example 45 as applied to a two-stage amplifier.

Figures 1, 2 and 3 illustrate three modifications in diagrammatic manner. Similar references denote similar parts in all three figures.

In said drawing T_1 , T_2 , T_3 , represent the 50 transformers, the cores of which are denoted by M_1 , M_2 , and M_3 respectively. The two thermionic valves 1 each comprise a plate 2, a grid 3 and a filament 4, the latter supplied 55 with current from a battery 5. P is the

main battery one pole of which is earthed and Z the telephone head piece.

In order to connect the mass of the telephone head piece Z to a point on the battery P all that is required is to connect one terminal of the telephone circuit to the said point on the cell and to connect the corresponding terminal of the telephone to the head piece. By doing this the connection is made through one of the conductors of the 65 telephone cord itself.

The secondary winding of the transformer T_2 , the potential of which is defined by connecting one of its terminals to the battery in order to avoid objectionable noises within 70 the thermionic valve, could, in fact, feed any external circuit.

Instead of connecting one terminal of the transformer T_1 , or T_3 , to the battery as shown in Fig. 1 one might connect to the battery the central point of the corresponding transformer winding as shown in Fig. 2 or the central point of a resistance or impedance connected in parallel with that winding, as shown in Fig. 3. 80

The connections from the battery to the different windings or masses to earth can be established through impedance capacities or resistances.

A two-stage amplifier has been illustrated 85 in the figure, but it goes without saying that the arrangement is suitable generally for an amplifier having any number of stages.

What I claim as new, and desire to secure 90 by Letters Patent of the United States, is:

1. In an amplifying apparatus for wireless signals and the like, a thermionic valve, a source of current in circuit therewith, a telephone, a transformer having a winding in circuit with said thermionic valve and source of current and a winding in circuit with said telephone, and a connection between the frame or casing of said telephone, the transformer winding in circuit with said telephone and one pole of said source 95 of current.

2. In an amplifying apparatus for wireless signals and the like, a thermionic valve, a source of current in circuit therewith, a telephone, a transformer having a winding in circuit with said thermionic valve and source of current and a winding in circuit with said telephone, a metal core for said transformer, and a connection between the frame or casing of said telephone, the trans- 105

former winding in circuit with said telephone, said metal core and one pole of said source of current.

3. In an amplifying apparatus for wireless signals and the like, a thermionic valve a source of current in circuit therewith, a telephone, a transformer having a winding in circuit with said thermionic valve and source of current and a winding in circuit with said telephone, and a connection between the frame or casing of said telephone, the transformer winding in circuit with said telephone and one pole of said source of current, said connection being grounded.
- 10 4. In an amplifying apparatus for wireless signals and the like, a thermionic valve, a source of current in circuit therewith, a telephone, a transformer having a winding in circuit with said thermionic valve and source of current and a winding in circuit with said telephone, a metal core for said transformer, and a connection between the frame or casing of said telephone, said metal core and one pole of said source of current, 15 said connection being grounded.

5. In an amplifying apparatus for wireless signals and the like, a thermionic valve comprising two electrodes and a grid, a source of current in circuit with said electrodes, a telephone, a transformer having a winding connected with said grid and one of said electrodes, a second transformer having a winding in circuit with said electrodes and said source of current and a winding in circuit with said telephone, and a connection between the frame or casing of said telephone, a winding of each of said transformers, and a pole of said source of current.

40 6. In an amplifying apparatus for wireless signals and the like, a thermionic valve comprising two electrodes and a grid, a source of current in circuit with said electrodes, one pole of said source of current being grounded, a telephone, a transformer having a winding connected with said grid and one of said electrodes, a second transformer having a winding in circuit with said electrodes and said source of current 45 and a winding in circuit with said telephone, and a connection between the frame or cas-

ing of said telephone, a winding of each of said transformers, and a pole of said source of current.

7. In an amplifying apparatus for wireless signals and the like, a source of current, a telephone, "n" thermionic valves connected in parallel with said source of current, each valve comprising two electrodes and a grid, "n+1" transformers connected with said valves one of said transformers having a winding adapted to be connected to an external circuit and a winding connected to the grid and one electrode of one of said valves, another of said transformers having a winding in circuit with the electrodes of another of said valves and a winding in circuit with said telephone, and a connection between the frame or casing of said telephone, the transformer winding adapted to 70 be connected to an external circuit, the transformer winding in circuit with said telephone, and one pole of said source of current.

8. In an amplifying apparatus for wireless signals and the like, a source of current, one pole of said source of current being grounded, a telephone, "n" thermionic valves connected in parallel with said source of current, each valve comprising two electrodes and a grid, "n+1" transformers connected with said valves, an iron core for each of said transformers, one of said transformers having a winding adapted to be connected to an external circuit and a winding connected to the grid and one electrode of one of said valves, another of said transformers having a winding in circuit with the electrodes of another of said valves and a winding in circuit with said telephone, 80 and a connection between the frame or casing of said telephone, said iron cores, the transformer winding adapted to be connected to an external circuit, the transformer winding in circuit with said telephone, and one pole of said source of current.

In testimony whereof I affix my signature in presence of two witnesses.

MARIUS C. A. LATOUR.
